SHOE TREE

Henry Clausing, Portsmouth, Ohio, assignor to
 Vulcan Corporation, Portsmouth, Ohio, a corporation of Ohio

Application January 15, 1943, Serial No. 472,447

5 Claims. (Cl. 12—128.2)

This invention relates to a shoe tree and particularly to that type of tree which is adjustable as to length, thus to adapt it for use in shoes of various length sizes, and which is also resiliently expansible transversely in its fore part portion.

The number and the complication of the component parts of the shoe tree embodying the invention has been greatly reduced. Furthermore the construction and inter-relation of its various elements are such that it consistently performs all of the functions necessary to correct distortion in and preserve the original contours of a shoe. As a result of the simplification in construction and the efficient coordination of the elements the present invention is exceptionally smooth and positive in operation and moreover is sufficiently strong to resist the maximum of hard usage and rough treatment over a long period of time.

The shoe tree is composed of three major elements, a heel part, a fore part and a strut member situated between and connected to each of the other elements. The heel part preferably is made adjustable along the strut member. A suitable means for such adjustments is provided by forming a threaded connection therebetween. In this manner the heel part may be adjusted along the strut member to lengthen or shorten the tree by rotating it in the same manner as a nut is rotated upon a bolt. The rear face of the heel part is shaped to fit into the heel of the shoe and snugly engaged substantially the whole height of the inner face of the rear extremity of the shoe upper.

The fore part is contoured to fit the shoe fore part and is divided lengthwise into two sections which are relatively laterally movable. The two sections are held together and guided in their lateral movements by a pair of transversely extending pins. Desirably one of the pins may be utilized as an axis upon which the strut member is pivoted. This pivotal connection between the fore part and the strut member enables the heel part to be moved downwardly into the heel part of the shoe when inserting the tree therein and also permits lifting of the heel part out of the shoe when removing the tree therefrom.

The forward end of the strut member is provided with a pair of spaced resilient figures which extend between the sections of the fore part which impart transverse resilient expansive force thereto. The expansive force thus imparted to the fore part insures proper correction of distortions which may exist in the shoe and acts to preserve the original contours thereof. The lengthwise adjustment above referred to adapts the last to

be received in shoes of a variety of sizes. Moreover a sufficient degree of lateral expansive movement in the fore part is provided to enable the tree to function efficiently in shoes having a variety of width sizes.

To present a better understanding of the invention a preferred embodiment thereof will now be described in connection with the accompanying drawing in which:

10 Fig. 1 is a perspective view of the shoe tree embodying the invention.

Fig. 2 is a plan view of the shoe tree illustrating its lateral compressibility.

Fig. 3 is a transverse sectional view on line 15 3—3 Fig. 2.

Fig. 4 is a transverse section on line 4—4 Fig. 2.

Fig. 5 illustrates a modified form of the invention.

While it is not essential that the shoe tree of 20 the present invention be made of wood a good grade of wood is, however, found to be a highly satisfactory material from which to make the tree. Inasmuch as wood is a nonessential material in the production of military goods its use 25 for the present purpose is highly desirable. Other materials such as moulded plastics having similar characteristics to that of wood may also be employed in the manufacture of the tree.

A desirable means for manufacturing the fore 30 part 5 of the tree is to turn it from a model upon a copying lathe such as a last lathe or any automatic contour lathe. After turning the fore part it is given a smooth surface and is bored transversely at its mid-section to form an aperture 35 6 within which a guide pin 7 is received. The fore part desirably extends rearward to a plane a short distance back of its ball portion 8 and desirably is rounded to present a semi-cylindrical boss portion 9 within which another aperture 10 is bored 40 to receive a pivot pin 11.

The boss portion 9 has formed therein a recess 12 substantially centrally of its transverse dimension. The fore part 5 is divided lengthwise into two sections in any desirable manner as for instance by a straight saw cut to a substantially central vertical median plane. The two sections 13 and 14 are normally held in spaced relation by means hereinafter to be described.

The heel part 16 desirably is cut from flat stock 50 of such thickness that the rear face 17 thereof may be satisfactorily shaped to fit the inner face of the rear portion of the shoe upper and to engage a substantial area thereof. The heel part is provided with a substantially horizontal aperture 55 18 having internal screw threads cut therein for

at least a portion of its length. The rear portion of the strut member 15 has threads complementary to those in the aperture 18. By interengaging the threads in the heel part with those upon the strut member an efficient means is provided for adjusting the length of the shoe tree.

The heel part 16 desirably is made symmetrical with respect to the axis of its aperture 18 and is provided with a pair of finger holes 19 which facilitate removal of the tree from the shoe. The symmetrical conformation of the heel part insures that it will function equally well in either of its two vertical positions thereby providing for adjusting the shoe tree length in increments of one-half of the pitch of the screw threads.

The forward portion of the strut member 15 desirably is of larger size than the rear threaded portion chiefly for the purpose of providing for the special structure to be found at this portion of the tree to impart resiliency to the fore part. A pair of spaced resilient fingers 20 are provided. The fingers may be separate elements secured to the strut member but preferably are integral therewith. A suitable method of constructing the strut to provide these resilient fingers is to cut a slot 21 of substantial width centrally along its axis in its enlarged end portion opposite its threaded end, thereby to present spaced integral fingers 20 upon the strut member 15. The proportions of the fingers 20 are calculated to provide the correct degree of resiliency.

The fingers 20 project into the recess 12 in the forepart between its two sections 13 and 14. The outside lateral dimension of the forward end of the strut member is such that it will closely fit within the recess 12 when the two sections of the fore part 13 and 14 are at their maximum separation.

The fingers 20 desirably also serve to connect the fore part to the strut. The outer ends of the fingers are bored to provide aligned transverse apertures 22 through which the pivot pin 11 extends. The apertures 22 are somewhat larger in diameter than the pin 11 thereby providing a limited amount of adjustment in longitudinal alignment between the fore part and the heel part. This flexibility of alignment will permit the shoe tree to accommodate itself to shoes having an unusual degree of displacement in the alignment of their heel and fore part from that of a normal last.

It will be readily understood that the fore part of a tree of proper size when placed in a shoe will be compressed against the resiliency of the fingers and may be compressed to any degree up to the condition where the fingers engage each other as illustrated in dotted lines in Fig. 2. Not only do the sections of the fore part have lateral movement but their interconnecting elements are so designed that the relative longitudinal alignment of each section may adjust itself to shoes of various contours.

The transverse relative movement between the sections 13 and 14 may be provided for in any desired manner. A suitable means to accomplish this end is illustrated in the drawing wherein the pins 7 and 11 are rigidly anchored in their respective apertures 6 and 10 within one of the fore part sections, for example section 13. The other ends of the pins 7 and 11 project into aligned portions of their apertures situated in the section 14 of the fore part. The apertures in section 14 have been enlarged sufficiently to loosely receive the pins.

The pin 7 is provided with means for retaining

the sections 13 and 14 from becoming completely disengaged one from the other. A suitable means for accomplishing this result is to provide the pin with a head 23 which desirably is rounded or 5 made completely spherical to insure freedom of movement of the parts. The outer portion of the aperture 7 in section 14 is counterbored sufficiently large freely to receive the head 23 and furthermore the counterbore preferably extends 10 inward a substantial distance to present a retaining shoulder 24 against which the head 23 bears. This shoulder preferably is situated relatively close to the inner face of the section 14 of the fore part. The headed pin means above 15 described for connecting the two fore part sections 13 and 14, permits relative angular movement between the sections as well as lateral expansion and contraction.

The side walls 25 of the recess 12 are disposed 20 at a slightly divergent angle as are also the inner faces 26 of the fingers 20. There are several advantages which flow from this construction. By referring to Fig. 2 it will be noted that when the fore part is contracted, the outer faces 25 of the fingers 20 which engage the inner walls 25 of the recess 12 will be found to interengage 25 for substantially the full length of the faces 25 because they assume substantially parallel positions. This position of the parts provides broad 30 interengaging surfaces which will function efficiently and reduce wear of the parts occasioned by manipulation of the tree when inserting or removing it from the shoe. Excessive wear and abrasion of the parts is avoided by thus insuring 35 that the area of the interengaging surfaces is relatively large.

A further advantage of the angular disposition 40 of the faces 25 resides in the fact that they contact the sections of the fore parts at a position well forward of the rear extremity thereof and substantially upon a central plane 27 of the ball portion 8 of the last. By engaging the fore part sections at this plane the expansive force of 45 the spring fingers is applied at the ball portion of the shoe which is the most effective position for the application of the expanding pressure.

The angular faces 26 of the spring fingers permit the outer faces thereof to approach each other more closely thereby increasing the total 50 scope of expansion of the fore part without increasing the dimensions of the co-acting parts.

In Fig. 5 is shown a modified form of the invention wherein the strut member 15 extends a substantial distance forward along the length of 55 the fore part 5 and is pivotally connected thereto upon an axis 31 substantially midway lengthwise thereof. The construction of the fore part is otherwise the same as that shown in Fig. 2. The angularly disposed faces 25 of the recess 12 are of necessity elongated but function in the same manner as described hereinabove. By thus positioning the axis 31, the spring fingers 20 engage the sections of the fore part sufficiently forward thereof to insure that a substantial portion 60 of the expansive force of the fingers will be transmitted to the forward extremities of the fore part sections. Thus in shoe styles having unusually broad toes sufficient expansion will take place to fill out and support all portions of the shoe fore part.

In applying the tree to the shoe the heel part is grasped as a handle to push the fore part into the shoe. As the tree enters the shoe the fore part sections are compressed which sets up lateral tension in the fingers 20 which tension in

turn is transferred to the shoe upper acting to smooth out wrinkles therein and to generally correct distortion and preserve the original shoe contours.

If the length of the tree is not correct for the shoe to which it is applied the heel part is rotated in one direction or the other until the correct length is found. The heel part is then pushed into its operating position bearing firmly against the inner face of the heel part of the shoe upper. The insertion and removal of the heel part is made possible by reason of the pivoted connection between the strut 15 and the fore part 5.

The finger holes 19 greatly assists in removing the tree from the shoe and furthermore provide a convenient means for hanging the tree upon a hook or other supporting means.

It may be found desirable to supplement the expansion of the fore part as set up by the fingers 20. This may be done by applying expansive pressure between the sections 13 and 14 at or adjacent the axis of the pin 7. This may be done in any suitable manner as by employing a coil expansion spring 29 shown in dotted lines in Fig. 4, which may surround the pin and bear upon the inner face of the fore part sections. To provide the necessary space for the coils of the spring when the fore part is compressed a chamber 30 may be provided in one or both of the sections 13 and 14.

In addition to the advantages above disclosed the present invention presents a very attractive appearance, is extremely simple to adjust and apply to the shoe and moreover has no metallic parts to cause abrasion or disfigurement of the shoe upper in which it is used.

I claim:

1. An all wood shoe tree comprising a heel part, a fore part longitudinally divided into two transversely expandable sections, a strut member between and connected to said heel and fore parts and having at least two laterally resilient spaced fingers integral therewith the outer ends of which extend between the sections of said fore part and act to impart resilient transverse expansive force thereto and means to adjust the length of the tree.

2. An all wood shoe tree comprising a heel part, a fore part divided lengthwise into two transversely relatively movable sections, an interconnecting strut member pivoted to said fore part, means for adjusting said heel part along said

strut member, at least two resilient fingers integral with said strut member the outer ends of which extend between the sections of said fore part and impart transverse resiliency thereto.

5. An all wood shoe tree comprising a heel part, a fore part shaped to fit a shoe fore part and divided lengthwise into the two transversely relatively movable sections, a strut member interconnecting said heel and fore parts, means at the rear end of said strut for adjusting said heel part lengthwise thereof, a slot at the forward end of said strut dividing it into a pair of laterally yielding fingers the outer ends of which extend between the sections of said fore part and impart resilient transverse expansive force thereto and a pivot pin secured in said fore part and projecting through apertures in said fingers thereby to provide a pivotal connection between said strut and said fore part.

10. An all wood shoe tree comprising a heel part, a fore part, an interconnecting strut member, means for adjusting the length of the tree, said fore part being divided lengthwise into two sections, means for guiding said sections relatively laterally including a pivot pin, said strut member having a slot in its forward portion dividing it into a pair of integral spaced laterally resilient fingers projecting between and imparting resilient expansive force to said fore part sections and having apertures therein through which said pivot pin passes thereby providing a pivotal connection between said strut and said fore part.

15. An all wood shoe tree comprising a heel part shaped to fit a shoe heel part, a fore part divided lengthwise into two sections, a strut member connecting said heel and fore parts, means for adjusting the length of the shoe tree, a slot in the forward end of said strut member presenting a pair of spaced transversely resilient fingers the outer ends of which project between and impart resilient expansive force to the sections of said fore part, a guide pin loosely connecting and guiding the forward ends of said fore part sections in relative transverse movement and a pivot pin rigidly fixed in one of said fore part sections and loosely received in the other section and to which said strut member is pivotally connected.

20. HENRY CLAUSING.
